UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

MEANS FOR DISCHARGING GRAIN AND SIMILAR MATERIALS FROM CARS OR OTHER CONTAINERS.

1,342,092.

Specification of Letters Patent. Patented June 1, 1920.

Application filed July 5, 1919. Serial No. 308,737.

To all whom it may concern:

Be it known that I, ARGYLE CAMPBELL, a citizen of the United States, residing at Chicago, in the county of Cook and State of Illinois, have invented a certain new and useful Improvement in Means for Discharging Grain and Similar Materials from Cars or other Containers, of which the following is a full, clear, concise, and exact description, reference being had to the accompanying drawings, forming a part of this specification.

My invention relates to improvements in means for discharging grain and similar materials from cars or other containers.

As is well known, it is customary for railroads to transport grain and other like bulk materials in ordinary box cars, the closure for the side doors being most frequently formed by means of planks nailed to the door posts. Such cars in the grain service are not entirely satisfactory for the reason that in unloading cars it is necessary to chop away some of the planks with the result that chips are mingled with the grain and some of the planks are always lost each time the car is unloaded.

While many experiments have been attempted to provide satisfactory means for discharging grain and like materials from ordinary box cars, the same have not proven entirely satisfactory, and the expense of providing such cars with discharge hoppers of usual construction is such that the railroads ordinarily cannot afford the same. As is well known, it is necessary, in unloading cars filled with grain and the like, to relieve the pressure behind the side door opening closure before the closures can be removed or shifted if the same are permanently attached to the car.

One object of my invention is to provide a simple arrangement which may be applied to either new or old box cars to adapt them for the carrying of grain and other materials carried in bulk, and without the necessity of incorporating any radical and expensive changes in the car.

Another object of the invention is to provide a simple and inexpensive discharge chute which may be applied to the side walls of a box car adjacent the usual side door openings and thereby permit the removal of a sufficient amount of grain from behind the

side door opening closures to thereby facilitate unloading of the cars.

Another object of my invention is to provide a relatively small and inexpensive grain-discharging chute which may be employed in conjunction with certain types of grain doors employed on some railway cars, which discharge chute will act as a relief door or auxiliary door for the main grain door.

The invention further consists in the improvements in the parts and devices and in the novel combinations of the parts and devices herein shown, described and made the subject matter of claim.

In the drawing forming a part of this specification, Figure 1 is an elevational view of a portion of a side of a box car taken at the center of the car opposite the usual side door opening and illustrating my improvements in connection therewith. In said figure, two applications of my improvements are shown, the full lines indicating my improvements applied to the side wall proper of the car and the dotted lines indicating the improvement applied to a grain door, in which latter instance my improvements act as a relief or auxiliary door for the grain door. Fig. 2 is an enlarged vertical sectional view taken substantially on the line 2-2 of Fig. 1. And Fig. 3 is a horizontal sectional view taken substantially on the line 3-3 of Fig. 1, and reproduced upon an enlarged scale.

In said drawing, 10 denotes the side wall of a box car of usual construction, said car having the usual side door openings indicated by the reference 11. The floor of the car is indicated by the reference 12, and 13 indicates a side sill of the car.

Referring to the construction illustrated in Figs. 2, 3 and the full line illustration in Fig. 1, my improved discharging arrangement comprises, broadly, the following elements: a discharge chute proper, indicated by the reference A, a door or cover, indicated by the reference B, and a lever, C.

The chute proper A, as shown, is preferably in the form of a casting and has upper and lower outwardly and downwardly extended walls 14 and 15 and vertical side walls 16-16. At its outer end the member A is formed with a relatively wide flange 17 adapted to lie against, or be countersunk

into, the outer boards 18 of the car wall and be secured to the car wall by any suitable means—such as bolts, 19—19, extending through said flange and through the wall of the car, as indicated in Figs. 1 and 2.

The thickness, horizontally, of the chute proper A is made such that the inner edge 20 thereof will lie flush with the inner boards 21 of the car wall so as to thereby 10 avoid any undesirable projections on the interior of the car. At its outer and lower end, the chute proper A is provided with a relatively narrow flange 22 extending all around the chute proper and defining the 15 exit or discharge mouth thereof. Said flange 22, as clearly shown in the drawing, projects beyond the flange 17.

The cover B is also preferably in the form of a casting and of a suitable size to close 20 the exit mouth of the chute A. Said cover or door B has preferably integrally formed therewith hinge lugs, indicated at 23, and the casting A has corresponding hinge lugs 24, so that the cover B may be pivotally 25 mounted on its bottom edge by means of the hinge pin 25.

The cover B is also provided with an inwardly extending flange 26 around all edges thereof and so proportioned as to snugly 30 fit over the flange 22 of the member A. In this way, a grain seal is provided whenever the cover B is in closed position.

The lever C is pivotally mounted on a headed pin or bolt 27 mounted in a boss 28 35 preferably formed integrally with the chute member A. Said lever C is provided with a cam face 29 adapted to coöperate with the corresponding cam rib 30 formed on the outer face of the cover or closure B. The 40 cams 29 and 30 are so formed that as the lever C is swung clockwise to the position shown in the drawings, the cover B will be forced securely against the chute proper A. To retain the lever C in proper position 45 when the cover B is closed, the member A is preferably provided with an outwardly extended bracket 31 having an upstanding arm 32 behind which the lever C is adapted to engage when the latter reaches its position 50 for locking the cover B. Further, to prevent tampering with the discharging device, the bracket 31 and the lever C are provided with perforated flanges 33 and 34 adapted to receive the usual railway lead 55 seal.

As will be noted from an inspection of Figs. 1 and 2 I locate my improved grain-discharging device closely adjacent the floor of the car and near the side post of the side 60 door opening. Only one of said discharging devices may be employed on each side of the car, or two or more may be employed, preferably one on each side of the side door opening. With this construction and location, it is evident that sufficient grain can

be discharged from the car adjacent the side door opening closure to relieve the latter of pressure from grain on its inner side and permit its being opened or removed. It will also be noted that my construction, in addition to being relatively inexpensive to manufacture, may be readily applied to old box cars now in service at very small expense, the only expense involved being that of the labor required to cut out the necessary opening in the car walls and bolt my device in place. Old box cars thus equipped with my device have a much greater usefulness than the ordinary box car; the expense of so equipping box cars is almost inconsequential; and there is no excessive dead weight or unproductive load added to the car.

Referring to the construction indicated by dotted lines in Fig. 1, the discharging device is the same in all respects as that hereinbefore described in detail, except that it is applied to a main grain door indicated by the reference D. The latter may be of any well-known design, such—for instance—as those which slide upwardly vertically on the inner face of the car wall for a limited distance and are then swung about pivots so that the door is hooked in inoperative position near the roof of the car.

Although I have herein shown and described what I now consider the preferred manner of carrying out the invention, the same is merely illustrative and I contemplate all changes and modifications that come within the scope of the claims appended hereto.

I claim:

1. In a box car having the usual side walls and side door openings and adapted for the carrying of grain, means for discharging part of a grain load through a side wall of the car, said means comprising: a chute located near the floor of the car and adjacent one side of a side door opening, a closure for the outer end of the chute, and means for locking the closure in closed position, said chute extending through the side wall of the car in a downward direction from the inner side to the outer side of the wall, said chute having an integral flange by which the chute is adapted to be fastened to the side wall of the car, said closure and lower outer end of the chute coöperating to form a grain seal when the closure is in locked position.

2. In a device of the character described, a chute having a flange extending therefrom and by which the chute is adapted to be secured to a wall, a door pivotally attached to said chute at its discharge end, and a lever, said lever being pivotally attached to the chute at one side of the door with the lever adapted to swing in a plane substantially parallel to the door when the latter is

in closed position and across the latter, said chute being provided with a bracket on the opposite side of the door to that where the lever is pivotally attached and into which 5 the lever is adapted to enter, said lever co-operating with the door to hold the latter in tight closed position when said lever is swung to enter said bracket.

3. In a device of the character described, 10 a chute, a flange for attachment extended therefrom, a door pivoted to said chute, and a lever, the flange being provided with a boss and with a bracket, the lever being pivoted to the boss and adapted to enter said 15 bracket, the door being provided with a camming face engaged by said lever to force the door into tight closure of the chute.

4. in a box car having the usual side walls and side door openings and adapted for the 20 carrying of grain, means for discharging part of a grain load through the side wall of the car, said means comprising, a chute located near the floor of the car and adjacent one side of the side door opening, a 25 closure for the outer end of the chute and means for locking the closure in closed position, said chute extending through the side

wall of the car in a downward direction from the inner side to the outer side of the wall and having a flange at its outer portion by which the chute is adapted to be secured to the side wall of the car, said closure and outer end of the chute coöperating to form a grain seal when the closure is in locked closed position. 30 35

5. In a device of the character described, a chute having a flange for attachment extended therefrom, a door pivotally attached to said chute, and a lever, said lever being pivotally attached to said flange of the 40 chute at one side of the door, said flange having a bracket formed integrally therewith on the opposite side of the door into which said lever is adapted to enter, the outer face of the door and the lever co-operating to force the door to tight grain-sealed position when said lever is entered within the said bracket. 45

In witness that I claim the foregoing I have hereunto subscribed my name this 14th 50 day of June, 1919.

ARGYLE CAMPBELL.

Witness:

META SCHMIDT.
